UNITED STATES PATENT OFFICE.

ANTONE J. ADAMEK, OF ORIENT, SOUTH DAKOTA.

BELT-TIGHTENER.

1,272,350.

Specification of Letters Patent.

Patented July 16, 1918.

Application filed April 21, 1917. Serial No. 163,685.

To all whom it may concern:

Be it known that I, ANTONE J. ADAMEK, a citizen of the United States, residing at Orient, in the county of Faulk and State of 5 South Dakota, have invented certain new and useful Improvements in Belt-Tighteners, of which the following is a specification, reference being had to the accompanying drawings.

10 This invention relates to an improved belt tightener and has for its primary object to provide an easily operated device for taking up slack in a driving belt when the same becomes loose upon the pulleys, and holding 15 the end portions of the belt while the same are fastened together.

It is another and more particular object of the invention to provide a device for the above purpose including a body bar having 20 means on one end for clamping engagement with one end of the belt, a second clamping device movable upon the body bar for engagement with the other end of the belt, and manually operable means for imparting a 25 step by step rotation in any direction to the latter clamp.

It is a further general object of the invention to simplify and improve the construction of devices of the above character, 30 render the same easily applicable and serviceable in practical use, and capable of manufacture at relatively small cost.

With the above and other objects in view, my invention consists in the novel features 35 of construction, combination and arrangement of parts to be hereinafter more fully described, claimed and illustrated in the accompanying drawing, in which:

Figure 1 is a side elevation of my im- 40 proved belt tightener;

Fig. 2 is a plan view thereof;

Fig. 3 is a section taken on the line 3—3 of Fig. 2; and

Fig. 4 is a section taken on the line 4—4 45 of Fig. 2.

Referring in detail to the drawing, 5 designates the body bar of the device having an angularly disposed, longitudinally extending flange or web 6 projecting from one 50 face thereof. The longitudinal edges of the bar 5 are provided with spaced notches forming the shoulders 7 therein, said shoulders being arranged in spaced relation.

Upon one end of the bar 5, a transversely 55 disposed frame 8 is integrally formed and projects from one side of the bar. This

frame has spaced, parallel portions, one of which terminates in an angular ear 9. 10 designates the clamping bar which is provided with an integral hand lever 11 and is 60 formed on its opposite ends with the angularly disposed lugs 12. In these lugs, the ends of a rod 13 are fixed, and the terminals of the rod are rotatably mounted in the ear 9 and in the body of the frame 8. A coil 65 spring 13' surrounds the rod 12 and bears at one of its ends against the clamping plate 10 and at its other end against the frame 8.

14 designates a slide member which is disposed upon one side of the body bar 5 and 70 has the curved lugs or flanges 15 extending over the upper and lower edges of said bar. This slide member is also provided with a clamping device, indicated at 16, which is identical in construction with the clamp on 75 the body bar above described in detail.

A lever 16' is disposed upon one side of the bar 5, said lever having retaining lugs 17 engaged upon the relatively opposite side of said bar. Between these lugs and the body 80 of the lever, the dogs 18 are loosely mounted upon the pins 19 for pivotal movement. The ends 20 of the dogs are adapted for engagement with the shoulders 7 upon the upper and lower edges respectively of the 85 body bar. The other ends 21 of said dogs are curved, as shown, and by their sliding contact with the edges of the body bar in the oscillation of the lever, the ends 20 of the dogs are caused to engage the shoulders 7. 90 A link 22 is pivotally connected at one of its ends, as at 23, to the lever 16' between the pivot bolts 19, while the other end of said lever is pivotally connected, as at 24, to one end of the slide member 14. The lever 16' 95 has a suitable handle 25 formed upon one of its ends, whereby the lever may be conveniently actuated.

In the use of the device, the ends of the belt to be stretched or tightened are engaged 100 between the oscillatable spring-pressed plates 10 of the respective clamping devices, and upon the release of the plates, the springs act to tightly clamp the ends of the belt between the movable clamping plates 105 and one arm of the respective frames 8 in which the plates are mounted. The lever 16' is now actuated by oscillating the same alternately in opposite directions so that the pivot bolts 19 of the dogs alternately serve 110 as fulcrums for the lever, the inactive dog which is not engaged with the shoulders 7

at one edge of the lever being movable with the lever, while the other of the dogs remains stationary. In this oscillation of the lever, the slide member 14 is, of course, moved longitudinally step by step along the body bar 5, and the belt is thus stretched or tightened around the pulleys on which it is engaged. The slack in the belt is thus taken up and the ends of the belt securely fastened together in any suitable or well known manner.

From the foregoing description, taken in connection with the accompanying drawing, the construction, manner of use, and several advantages of the device will be clearly and fully understood. It will be seen that I have produced a very simply constructed, durable, and serviceable belt tightener which can be very easily and quickly applied to the belt or removed after the stretching operation. The several elements are all of very simple form and it will, therefore, be manifest that the invention can be manufactured at relatively small cost.

While I have herein shown and described the preferred construction and arrangement of the several parts, it is to be understood that the same are susceptible of considerable modification therein and I, therefore, reserve the privilege of adopting all such legitimate changes as may be fairly embodied within the spirit and scope of the invention as claimed.

Having thus fully described my invention, what I desire to claim and secure by Letters Patent is:

A belt tightener including a body bar substantially T-shaped in cross section, the

longitudinal marginal portions of the head of said bar being provided with spaced notches to afford shoulders, the shoulders of one margin being in staggered relation relative to the shoulders of the second margin, a lever having an end portion overlying the outer face of the head of the bar and provided with lugs underlying the longitudinal margins of the head of the bar, arcuate dogs arranged at opposite sides of the head of the bar, each of said dogs being pivotally engaged intermediate its length with the lever, one end of each of the dogs being engageable with the adjacent shoulders in the bar and the opposite end of said dog contacting with the adjacent longitudinal edge of the head of the bar, a slide mounted upon the head of the bar, a link pivotally engaged at one end with a lever at a point midway between the pivotal connections of the dogs with the lever, the opposite end of the link being pivotally engaged with the slide at substantially the transverse center of the head of the bar, belt clamping means extending upwardly from the slide, and belt clamping means carried by an end portion of the head of the bar, said lever being positioned between the clamping means carried by the bar and the slide and capable of swinging movement and movement longitudinally of the bar.

In testimony whereof I hereunto affix my signature in the presence of two witnesses.

ANTONE J. ADAMEK.

Witnesses:

W. H. PETERSON,
GEO. I. GUNNISON.
